UNITED STATES PATENT OFFICE

2,557,919

NEBULIZER OR THE LIKE

George P. Trumbour, Needham, Mass., assignor
to MacGregor Instrument Company, Needham,
Mass., a corporation of Massachusetts

Application December 19, 1947, Serial No. 792,656

2 Claims. (Cl. 299—88.5)

1

My present invention relates to nebulizers or like devices.

The most important requirement of such devices as nebulizers is, of course, that they be adapted to operate efficiently with various different liquids. In order that nebulizers, capable of such operation, may be produced economically by the manufacturer and be of maximum utility to the purchaser, it is necessary that their component parts be interchangeable to enable them to be embodied in detachable assemblies thereby to facilitate their production and to enable the users to take them apart for thorough cleansing or other service. For such purposes, molded plastic parts are admirably adapted because of economy to the manufacturer, the minimization of breakage, and the attractiveness of appearance that the use of plastics facilitates.

In accordance with my invention I provide a nebulizer or like device which consists of a hollow body, the lower part of which constitutes a well and the upper part of which has an outlet and a port in which an air delivery conduit is removably seated with an end extending into the hollow body. A member in the body has a passage in one end disposed and dimensioned to receive within it the extremity of the delivery conduit so that it is detachably supported thereby and an orifice disposed towards the outlet and in communication with the passage. The other end of the member and the suction conduit have complementary interlocking portions engageable to detachably support the suction conduit with its lower end adjacent the bottom of the well and the orifice in its upper end operatively disposed with reference to the other orifice. Both the member and the suction conduit are removable through the outlet and the outlet itself may support a removable cap having a discharge port.

In the accompanying drawings, I have shown an illustrative embodiment of my invention from which these and other of its novel features and advantages will be readily apparent.

In the drawings:

Fig. 1 is a vertical section through a nebulizer in accordance with my invention.

Fig. 2 is a section along the lines 2—2 of Fig. 1, and

Fig. 3 is an exploded view, in perspective, of the air delivery and suction conduits and the member by which they are operatively connected.

In the embodiment of my invention shown in the drawings, I have indicated at 5 a hollow and preferably open-ended, cylindrical body 5 having a supporting base 6. The lower part of the body

2

5 constitutes a well for the liquid to be atomized and is preferably formed with an offset pocket 7.

The body 5 also has a port 8 in its side in which the air delivery conduit 9 is seated, when its flange 10 engages the side of the body 5, with its extremity 11 extending therein. The other end of the air delivery conduit 9 is shown as having secured to it a conventional bulb 12.

At 13, I have indicated a suction conduit, the lower end of which is to extend into the well-adjacent the bottom of the pocket 7 and the upper part of which is formed to establish a head 14 having a laterally opening orifice 15 below which it has a recess establishing a pair of shoulders 16 and 17 of which the lower shoulder 17 extends a substantial distance beyond the extremity of the shoulder 16.

The shoulders 16 and 17 are vertically spaced to receive between them and detachably support one end of the member 18, the other end of which is formed with a passage 19 dimensioned to receive within it the extremity 11 of the air delivery conduit thereby to be detachably supported by it and to maintain the suction conduit 13 in its proper position when it and the member 18 are assembled. The member 18 has an orifice 20 in communication with the passage 19 and disposed to be located closely adjacent the extremity of the shoulder 16 in operative relation to the orifice 20 when the member 18 and the suction conduit 13 are assembled, whereby air passing through the delivery conduit 9 is effective to draw liquid upwardly through the suction tube 13 and to atomize it.

In the embodiment of my invention shown in the drawings, the mouth of the body 5 is closed by a cap 21 having a vertically disposed outlet 22 and a shoulder 23 to seat on the mouth 7 and to establish a sleeve 24. The outside diameter of the sleeve 24 is slightly less than the inside diameter of the body 5 to fit tightly therein and its length is such as to extend downwardly into the body 5 beyond the upper ends of the head 14 of the suction tube 13 and the member 18. Its inside diameter, at least in the zone of said upper ends, while greater than the maximum cross sectional dimensions of the assembled suction tube 13 and the member 18, to receive their upper ends, provides clearance less than the depth of the shoulder 16.

As will be apparent from the drawings, the sides of the suction conduit head 14 and the member 18, opposite their interlocking portions, are rounded and when assembled together and supported by the extremity 11 of the air delivery

conduit 9, the orifice 20 is in the vertical axis of the body 5 and the rounded sides are arcuate with respect to that axis.

By this construction, the suction tube 13 and the member 18 may be readily assembled and inserted, as a unit, into the body 5 when its cap 21 is removed and may be easily held so that the member 18 receives the extremity 11 when the air delivery conduit 10 is seated or unseated. While the member 18 and the suction conduit head 14 are securely locked together, the sleeve 24 prevents their accidental disconnection. By removing the cap 21, my nebulizer may be as readily disassembled.

While some or all the parts may be made of other materials, I prefer that they be of any suitable plastic stock to ensure economy in manufacture and that the parts are interchangeable to provide, through ease of assembly or disassembly, maximum advantage to the purchaser in use.

What I therefore claim and desire to secure by Letters Patent is:

1. A nebulizer or the like comprising a hollow open-ended body, the lower part of which constitutes a well and the upper part of which has a port, a suction conduit having a laterally disposed orifice adjacent its upper end and having a recess below and in vertical alinement with said orifice, an air delivery conduit frictionally seated in said port to be supported by said body, a member in said body having one end dimensioned to fit frictionally said recess, a passage in which the extremity of said delivery conduit is seated to support said member and to connect said suction tube thereto when said member is seated in said recess, and an orifice disposed upwardly and in operative relationship to said other orifice and in communication with said passage, and a cap for said body, said cap having an upwardly opening port and including a shoulder to seat on the mouth of said body and a sleeve having its outside diameter equal to the inside diameter of said body and its inside diameter slightly greater than the maximum cross sectional area of said suction conduit and member, when assembled together and positioned by said delivery conduit and extending downwardly into said body below the upper end of said suction conduit, said suction tube and said member being removable as a unit through the open end of said body when said cap is removed and said air delivery conduit is withdrawn from said body and having their upper portions located adjacent said open end.

2. A nebulizer or the like comprising a hollow open-ended body, the lower part of which constitutes a well and the upper part of which has a port, a suction conduit having a laterally disposed orifice adjacent its upper end and having a recess below and in vertical alinement with said orifice, an air delivery conduit frictionally seated in said port to be supported by said body, a member in said body including flat, parallel top and bottom surfaces and being dimensioned to fit frictionally into said recess with said surfaces in engagement with said shoulders, said member having a passage in which the extremity of said delivery conduit is seated to support said member and to connect said suction tube thereto when said member is seated in said recess, and an orifice disposed upwardly and in operative relationship to said other orifice and in communication with said passage, and a cap for said body, said cap having an upwardly opening port and including a shoulder to seat on the mouth of said body and a sleeve having its outside diameter equal to the inside diameter of said body and its inside diameter slightly greater than the maximum cross sectional area of said suction conduit and member, when assembled together and positioned by said delivery conduit and extending downwardly into said body below the upper end of said suction conduit, said suction tube and said member being removable as a unit through the open end of said body when said cap is removed and said air delivery conduit is withdrawn from said body and having their upper portions located adjacent said open end.

GEORGE P. TRUMBOUR.
